UNITED STATES PATENT OFFICE.

DANIEL B. SHEFFIELD, OF VENICE, CALIFORNIA.

HAIRPIN.

1,319,671.

Specification of Letters Patent.

Patented Oct. 21, 1919.

Application filed June 21, 1917. Serial No. 176,162.

To all whom it may concern:

Be it known that I, DANIEL B. SHEFFIELD, a citizen of United States, residing at Venice, in the county of Los Angeles, State of California, have invented certain new and useful Improvements in Hairpins; and I do hereby declare the following to be a full, clear, and exact description of the invention, such as will enable others skilled in the art 10 to which it appertains to make and use the same.

This invention relates to improvements in hair pins and is directed more particularly to an improvement on the structure dis- 15 closed in Patent No. 1,126,752 issued February 2, 1915.

An object of the present invention resides in the provision of a hair pin embodying a pair of outer leg portions and a pair of central coöperating locking legs, constructed and arranged to so engage a plurality of strands of hair as to hold the pin firmly in 20 position and against loss or displacement.

With the above and other objects of simi- 25 lar nature in view, the invention consists in the construction, combination and arrangement of parts, set forth in and falling within the scope of the appended claim.

In the drawing:

30 Figure 1 is a front elevation of a hair pin constructed in accordance with the invention,

Fig. 2 is a side elevation thereof, and

35 Fig. 3 is an enlarged section taken on the line 3—3 of Fig. 1.

Referring now more particularly to the accompanying drawing, my improved hair pin is formed from a single strand of resili- 40 ent wire and consists of the main or outer legs 5 which are corrugated as at 6 at their inner ends.

Between the legs 5 are provided a pair of

central coöperating locking legs 7, 7 which are formed by doubling the central portion of the wire and twisting together the result- 45 ant loops at their inner ends as indicated at 8.

Between their ends, the legs 7, 7 are bent angularly, first in divergent relation and then returned in convergent relation to pro- 50 vide oppositely directed humps 9 and are finally bent at their outer or free ends in divergent relation as shown at 10.

When thus constructed, the legs 7, 7 are adapted, as the pin is inserted into the hair 55 in the usual manner, to pass on opposite sides of a plurality of strands of hair so that the latter will enter the space formed between the humps 9. By thus disposing the hair between the legs 7, 7 the latter will co- 60 operate, as will be readily understood in holding the pin firmly in position, it being impossible for the hair to pass from between the legs 7, 7 unless the pin is grasped and withdrawn, so that possibility of accidental 65 loss or displacement of the pin will be pre- cluded.

What I claim is:

A hair pin formed from a single piece of wire and comprising a pair of outer leg por- 70 tions and a pair of central coöperating lock- 75 ing legs formed by doubling the central por- tion of said wire, said locking legs being twisted as to their inner ends and being bent between their ends first in divergent and then in convergent relation to provide op- positely directed humps and being finally bent terminally in divergent relation.

In testimony whereof, I affix my signature in the presence of two witnesses.

DANIEL B. SHEFFIELD.

Witnesses:

E. H. CONYERS,
G. B. REID.
